UNITED STATES PATENT OFFICE.

EDWARD J. GULICK, OF ELKHART, INDIANA, ASSIGNOR TO C. G. CONN, LTD., OF ELKHART, INDIANA, A CORPORATION OF INDIANA.

MILLING MACHINE FOR MUSICAL-INSTRUMENT KNOBS.

Application filed October 30, 1922. Serial No. 597,731.

To all whom it may concern:

Be it known that I, EDWARD J. GULICK, a citizen of the United States, residing in the city of Elkhart, county of Elkhart, Indiana, have invented certain new and useful Improvements in Milling Machines for Musical-Instrument Knobs, of which the following is a specification.

This invention relates to improvements in the manufacture of musical instruments, and particularly to the manufacture of saxophones.

In brass instruments, and particularly saxophones, modulations of the tone produced are effected by the control of valves which establish or close communication between the interior of the instrument body and the air. These valves are plates provided on their operative surface with a cushioning element and their application to or removal from the valve seat is effected by lifting the plates through a lever arrangement which the player actuates with his fingers. The fulcrums for the valve levers are formed by knobs and the present invention is directed to improvements in a machine by means of which the heads of the knobs serving as supports for the fulcrum pins may be suitably machined to accommodate the pins and the levers for the valve plates.

It is therefore an object of the invention to provide a machine in which through suitable adjustment of the instrument body with respect to one or a plurality of tools the operative relation between the knobs and the tools may be established, whereby upon driving said tools the knobs are machined.

It is also an object of the invention to arrange a plurality of rotary cutting tools, as for instance ordinary milling cutters, on a single shaft, in spaced relation corresponding to the spaced relation which knobs located in the same axial plane of the saxophone body occupy.

The invention also has the object of combining a plurality of carriers of milling cutters or the like in a single support and to provide for the adjustability of this support so as to selectively place any one of

these carriers into operative relation with the drive of the machine.

Another object of the invention is to provide for the adjustment of the instrument body in such manner that the body may be rotated about its axis and may be secured in the adjusted position to bring a knob or an axial series of knobs into operative relation with respect to the cutters or with respect to that assembly of cutters which, through selective adjustment of the common support of the cutter carriers, has been placed in a predetermined position.

The invention also contemplates to provide a machine in which normally the instrument body is retained in an inoperative position and in which the transfer of this body after suitable rotary adjustment thereof to an operative position, may readily be effected by the movement of a single lever.

The invention also contemplates the provision of means whereby the movement of the saxophone body to operative or inoperative position is automatically limited and whereby particularly the movement of the body to operative machining position is limited so that excessive depth of operation of the milling cutters is avoided.

The invention also has the object of providing in a machine of this character means for positively locking the common support of the carriers of the milling cutters in one of several predetermined positions to prevent inexact adjustment of the carrying shaft for an assembly of cutters.

The invention also has the object of including in a machine of this character means for positively locking the instrument body in any one of a plurality of positions after rotary adjustment to assure that the knob or knobs to be machined are exactly in that position in which the operation can be performed with the highest degree of efficiency and speed.

The invention also has the object of providing a single drive shaft for a plurality of carrying shafts for the milling cutters and to effect the operative connection of the single drive shaft with the selected shaft of the milling cutters only when the source of

power is placed in operative relation with respect to the machine, whereby automatically this driving relation between the drive shaft and the selected cutter shaft is interrupted upon interruption of the drive to prevent accidental displacement of the selected cutter shaft from operative position.

The invention also has the object of providing a support for the saxophone body which is movable to such an extent that the insertion of a saxophone body on a mandrel or the removal of the body from the mandrel may rapidly be effected without interfering with the rapidity with which a second bearing for the saxophone body may be placed to operative position to retain the body during operation.

With these and numerous other objects in view, an embodiment of the machine is illustrated in the accompanying drawings, the novel features being pointed out in the appended claims, and is described in the following specification.

In the drawings:

Fig. 1 is a front elevation of the machine with parts shown broken away;

Fig. 2 is a top plan view on the operative elements of the machine;

Fig. 3 is an end elevation of the machine;

Fig. 4 is a sectional view on the line 4—4 of Fig. 1 on a somewhat larger scale, showing the support of a carrier for the cutter shafts;

Fig. 5 is a horizontal section on line 5—5, Fig. 1, through the drive and clutch for the cutter shafts;

Fig. 6 is a detail view, partly in section of the actuating elements for the clutch;

Fig. 7 is a sectional view on a larger scale on line 7—7, Fig. 1, through the end of the mandrel supporting shaft;

Fig. 8 is another sectional view on line 8—8 of Fig. 1;

Fig. 9 is a side elevation of a cutter;

Fig. 10 shows a clutch head in elevation;

Fig. 11 is a front view of the same;

Fig. 12 is a front view of the companion clutch collar;

Fig. 13 is an edge view of the same;

Figs. 14, 15 and 16 are elevations of different knobs;

Fig. 17 shows partly in section and partly in elevation a clamp bearing for the mandrel, and

Fig. 18 is a sectional view and part elevation of the device for fixing the saxophone body on the mandrel.

Fig. 19 is a detail view of the end of one of the tool spindles.

The machine comprises standards 1 on which a bed 2, similar to the bed of a lathe, is supported. The bed carries on its top surface a head bearing 3 and a tail bearing 4; the latter may be longitudinally adjustable thereon, the bed having a T-groove 2'

to receive the heads of clamping bolts 4' inserted through the base of the bearing (Fig. 8). This renders possible the use of cutter shafts of variable length. The bearings 3 and 4 serve for rotatably carrying the supports of the cutter shafts.

The head bearing 3 consists of a split and approximately cylindrical casing 5 in which is rotatably fitted a drum support 6 for jack shafts or extensions of the cutter shafts (Figs. 4, 5). In the illustrated embodiment three of these extensions 7 are shown, each being mounted in a journal sleeve 8 which is located in a bearing 9 of the drum 6. The tubular bearings are connected with a central sleeve 10 and the latter is keyed to a rotatable bar 12 which extends therethrough. For retaining the drum 6 and thereby also the extensions 7 in selectively predetermined position relatively to the bed, a locking device is provided comprising a spring controlled plunger 11, Fig. 4, which is slidable in a tubular extension 14 secured to the casing 5. The upper end of this plunger carries a knob 15 having a cam surface 16 which cooperates with a companion cam surface 13 on the sleeve 14, whereby upon rotation of the knob 15 in one direction the plunger will be withdrawn against the tension of the spring while upon rotation of the knob in opposite direction the spring will force the plunger 11 with its reduced end 18 into one of the three sockets 19, which are provided on the circumference of the drum 6. The tail bearing 4 also rotatably supports the bar 12, on which is fixed a spider 20 carrying removably the ends of the tool spindles 21.

The mechanism for individually and selectively driving these spindles comprises a motor 22 on a bracket 23 and having a pulley from which a driving belt 24 extends to a pulley 25. The pulley is connected by means of the bolts 26 and web 27 (Fig. 5) with the flange 28 of a bushing 29 secured to a countershaft 30 by a key. The bushing and countershaft are supported in the bearing 31 forming part of a bracket 32 which is secured to the bed of the machine. This bearing has a flange 33 in marginal abutment with a cylindrical extension 6' of the drum 6, to form a housing for the extensions 7. In this way the drum 6 with the bearing for the central bar 12 therein may be rotated while maintaining permanently closed the chamber in which these parts are located. The rotation of the drum 6 is effected by means of one or more handles 36 which project from this drum extension 6'.

The countershaft 30 ends in a coupling head 34 provided with a plurality of claws and the shaft extensions 7 also are provided at their ends with collars 35 adapted for operative engagement with the head 34 of the countershaft.

The tool shafts 21 which carry the cutters 37 are readily attachable to and removable from the shaft extensions 7, from which they are driven, as they are provided with flattened end portions 21' adapted to enter the recesses 38 in the shaft extensions 7. Their projecting ends have screw threads at 39 whereby the nuts 40, Figs. 1 and 2, may be secured partly on the interengaging ends 19 of the extensions 7 and tool shafts 21 to prevent axial displacement of these parts.

Brackets 41 which are secured at the front end of the bed by means of clamping bolts 42 entering a longitudinal T-groove carry 15 each a bearing 43 for a rock shaft 44. This rock shaft is provided with longitudinally adjustable clamping collars 45, 46, on which the bearings for the mandrel are supported, so as to be rotatable in the plane of the top 20 surface of said collars.

The head bearing 47 for the mandrel 50 comprises a cylindrical casing with a horizontal axis and having in its lower part a socket 48 with a vertical axis. A cylindrical extension 49 provided with a groove 51 projects from the collar 45 into the cylindrical bore 48. A short key 52 seated in the groove 51 of the extension 49 traverses a portion of the bearing 47. This permits of 25 rotary movement of the bearing 47 with respect to the pedestal or collar 45, prevents however displacement in upward or downward direction.

The mandrel 50 is secured to the stem 50' 35 which is supported in the bearing 47 and which is provided within the bearing on its circumference with several sockets 53 to receive the locking pin 54 at the end of a spring controlled plunger 55, guided in a 40 tubular extension 56 of the bearing 47. The sleeve terminates in a cam surface 57 in cooperation with a companion surface 57' on a knob 58 fixedly connected with the plunger, Fig. 7. Upon part rotation of the 45 knob in one direction the plunger will be withdrawn by the cam action against the tension of the spring while upon rotation in the other direction the spring will cause the locking pin to enter into one of the sockets 50 on the stem 50', provided the latter has been turned to bring a socket into alinement with the plunger. The location of the 55 sockets on the mandrel stems circumferentially corresponds with the circumferential distribution of the knobs K or of axial series of knobs on the saxophone body S.

The mandrel 50 is a conical partly tubular element having at the smaller end an axial extension pin 59. This pin is supported in a clamp bearing 60 mounted on the collar 46. The bearing 60, which is partly split longitudinally, carries a journal bar 61 having at one end a socket to receive the reduced pin 59 of the mandrel. The two 65 split parts are provided with alined bosses

of which the lower one is tapped. A clamping screw 62 extends into the tapped portion and loosely through the other boss and is provided at the projecting end with a handle and with a collar. Upon turning the handle in one direction the two split portions of the bearing will be forced toward each other while upon movement in opposite direction the pressure will be released, whereupon the journal bar 61 may be slid axially within the bearing to release the pin 59, permitting the removal of the mandrel or to provide a seat for this pin. The base plate of the bearing 60 is provided with two arcuate slots 63 through which 69 clamping screw extend into the collar 46, whereby the tail bearing of the mandrel may be angularly adjusted and locked in proper position.

A lever 64 is attached to the rock shaft 35 44 by means of a collar and serves as a handle whereby this shaft may be turned about its axis. Another collar 65 adjacent the first named collar has a downwardly extending arm (Fig. 8) 66 through the ends of 69 which an adjustable stop screw 67 extends. This stop will contact with the bracket 68 on the bed of the machine when the shaft 44 is rocked downward through a certain 63 are. For adjustably limiting the operative 100 rocking movement of the shaft in the opposite direction, a stop screw 69 projects adjustably through the bracket 68, the point of the screw contacting with a boss on the arm 66 when the lever 64 and shaft 44 are swung in the opposite direction.

As both of the bearings 47 and 60 are independently adjustable about vertical axes, their distance also being adjustable through displacement of the clamp collars 45, it is obvious that the mandrel may be adjusted to have its axis at an angle to the axis of the bar 12. In this manner the engagement of all of the tools 37 on a selected spindle 21 with all of the heads of the knobs K of a 110 series is assured in that manner which is required for properly milling or grinding the same. It is also obvious that regardless of the length of the bed of the machine, 115 mandrels of different length and of different taper may be mounted on the machine and that simultaneous engagement of the tools with those knobs K may be effected which are axially alined on the surface of the saxophone body S. The rocking movement of the shaft 44 effected by the lever 64 regulates the depth to which the cutters engage the heads of the knobs. From Fig. 8 it is apparent that, owing to the mounting 120 described, the axis of the mandrel when in operative position is not parallel to the axes of the bar 12 or spindles 21, but that that surface line of the saxophone body which carries the knobs to be worked is parallel 125 to said axes.

The belt 24 is normally of such length as to slip over the rim of the pulley 25 without causing the drive of the same. In order to bring the belt into operative relation, a 10 tightener pulley 70 is mounted on an arm 71 secured to a lever 72 which is pivotally supported in a bracket 73 at the end of the machine. A spring 74 anchored at its upper end in the bed, as shown in Fig. 1, tends to pull the lever 72 upwardly to retain thereby the idler pulley in inoperative 15 position. In order to move this pulley to operative position a link 75 pivoted to the lever 72 extends to another arm 76 which is fixedly secured on a rock shaft 77 supported near the bottom of the bed and provided with a treadle arm 78 which projects forwardly within convenient reach of the operator to be manually engageable by him. 20 Upon depression of the treadle the rock shaft will effect a swinging movement of the lever 72 to force the idler 70 towards the belt and to tighten the same. Upon release of the treadle the spring 74 will pull the rock shaft into normal position owing to the connection of the spring with the arm 72, and owing to the connection of this arm with the rock shaft 77.

25 The same treadle shaft also serves for placing the drive shaft 30 into operative position, and it may also serve for applying a brake to the pulley or, respectively, for withdrawing the brake. A link 80 which is flexibly connected to the treadle shaft 77 by means of arm 81 extends upwardly and is, through arm 82, in connection with a collar 83 which is loosely mounted on a rod 84, slidably secured in the bed of the machine. This rod extends at one end through a bushing 85, Fig. 6, secured to a vertical web of the bed. The collar 83 to which the link 80 is connected is provided with a cam surface 86 in cooperation with a companion surface 86' on a collar 87 fixed to the rod 84. 40

45 If, therefore, the treadle arm 78 is depressed, the link 80 will be forced upward, causing a displacement of the rod to the left as shown in Fig. 1. The outer projecting portion of the rod is pivotally connected with the lower end of a lever 88 which is fulcrumed at 89 on a bar 90 projecting from the bracket 32. The upper end of this lever is bifurcated and is provided with pins 91 extending into an annular groove of a split collar 92 (Fig. 5), which is rotatably connected with the drive shaft 30 but which is held against axial displacement on the said shaft. Upon displacement of the rod 84 to the left, as described, the lever 88 will be moved inward at its upper end, thereby forcing the collar and the shaft 30 inward and bringing the coupling element 34 into operative position relatively to that extension 7 which had been placed into operative position by the previous rotation of the

drum 6. When the treadle arm 78 is released the treadle shaft 77 will again be restored to its original position by the spring 74, thereby also causing the return of the lever 88 to a position in which shaft 30 is withdrawn from coupling position.

A lateral projection 93 on the lever 88 is adapted to engage a brake shoe 94 indicated in dotted lines in Fig. 1 and normally engageable with the rim of the pulley 25 on a rim portion which is not surrounded by the transmission belt 24. If, therefore, the treadle shaft is actuated the projection 93 of the lever 88 removes the brake shoe from engagement with the rim, and upon return of the treadle shaft to normal position the brake shoe is forced immediately against the pulley to stop rotation of the shaft 30.

The operation of the device will be understood from the above description.

The various knobs K on the tubular tapering bodies of brass instruments or the like, and particularly the knobs of saxophones, are distributed on the outer surface in such manner that some of these knobs, although spaced irregularly from each other, are in axial alignment, in which case a plane may be defined by the common axis of these knobs and by the axis of the saxophone body.

The body S is placed on the mandrel and secured against displacement by a knob 100, having a reduced portion 101 threaded at 102 to cooperate at the threaded portion with a screw 103 in the stem 50' of the mandrel, said knob reduced portion, which engages in a suitable recess in the stem 50', serves also to retain the mandrel 50 securely on said stem, Fig. 18. The mandrel 50 for supporting the saxophone body S is then secured in place, and is held in one of several rotatably selective positions by means of the locking pin 54. Six of these selective locking positions are indicated in Fig. 7, although it is obvious that the number of these positions may vary with different types of instruments. The opposite end of the mandrel is secured by means of the reduced extension in the slide clamp bearing shown in Fig. 17. This slide clamp bearing and the bearing at the larger end of the mandrel are then adjusted in such manner that upon rotation of the shaft 44, on which the bearing brackets 45, 46 are clamped, the mandrel will be moved relatively to axes of the cutter shafts in such manner that the mandrel line of the saxophone body containing the knobs to be machined is parallel to the axis of the cutter shafts.

The cutters 37 on the three cutter shafts 21 are naturally spaced axially in accordance with the arrangement of the knobs to be finished by the same. It may be advisable to leave the cutters on their shafts in these

positions after they have once been placed thereon, and to utilize different shafts for different types of instruments or for the same type of instrument but for different series of knobs. The operator will therefore select three units of cutter shafts and cutters in accordance with the requirements of the saxophone body to be finished. From Figs. 1, 2, 14, 15 and 16 it will be apparent that in some sets, in which knobs are in axial alignment with each other, some knobs may require unilateral milling on one side, Fig. 14; other knobs may require a unilateral milling on the other side, and some knobs (Figs. 15, 16) may again require lateral milling on both sides or bilateral milling. These three units of cutters and cutter shafts are inserted into their supports 6 and 20. the left hand ends of the cutter bearing 20 shafts 21 are operatively united with the corresponding shaft extensions 7 through nuts 40. The operator then rotates by means of the handles 36 (Fig. 1) the support 6 into that position in which the selected shaft 21 and cutters 37 are in operative relation to the body. In this position that shaft extension 7 which is associated with the selected shaft 21 is in opposition to the drive shaft 30. After this adjustment of the cutter shafts 21 through rotation of the drum 6 has been effected, this drum is locked by the locking pin 13, Fig. 4.

The lever 64 for controlling the supporting shaft 44 of the bearing brackets for the mandrels is still projecting downward; the mandrel 50 and the bearings 47, 60 supporting the mandrel are at such distance from the cutting edges of the tools 37 that the knobs K are below a horizontal plane 40 which contains the axis of the selected shaft, and also that of the supporting bar 12 for the plurality of shafts 21. The parts are in a position different from the position shown in Fig. 8, the stop screw 67 near the 45 lower end of the arm 66 being then in engagement with the bracket 68.

After this adjustment of these parts the operator depresses the treadle arm 78 and thereby causes the tensioning of the belt 24, 50 whereby the pulley 25 and shaft 30 are driven by a predetermined rate of speed. This depression of the treadle shaft also actuates the clutch lever 88 shifting the shaft 30 axially into a position in which its clutch 55 head 34 enters into operative engagement with the corresponding coupling collar 35 of the selected shaft extension 7. Simultaneously with the tightening of the belt 24 and with the movement of the clutch lever 88 to throw the shaft 30 and coupling 34 to operative position, the brake shoe is released from the pulley and the pulley is therefore ready to assume its normal speed at great acceleration.

60 The operator now lifts the lever 64 to

rotate the bearing supporting shaft 44 until the parts reach the position indicated in Fig. 8 and in which a further movement of the shaft 44 is arrested by the adjustable stop 69. This movement slightly lifts the 70 bearings 47, 60 for the mandrel and at the same time moves the bearings with the mandrel and the saxophone body secured thereto into the operative position, Fig. 8, in which one series of knobs may be milled 75 as required by the cutters 37 properly arranged and spaced from each other on the selected cutter shaft 20. As the milling operation requires relatively short time, the operator may arbitrarily apply greater or less force to the lever for maintaining the horizontal rock shaft 44 in operative position, or, if the material to be treated should prove exceedingly hard, the operator may intermittently lower the lever to prevent 80 overheating of the parts and then again raise the parts to operative position until the operation is completed.

In order to mill the knobs in another series, the operator loosens the slide clamp bearing 60 and rotates the mandrel after withdrawal of the locking pin 54, inserting this locking pin again after another one of the six series of knobs shown in Fig. 8 has been moved into such position that upon returning of the parts to operative relation, Fig. 8, this other series will be located in a horizontal plane containing the axis of the selected cutter shaft and the axis of the common support. As the knobs in this second series 90 may be staggered longitudinally in a manner different from the knobs of the series previously treated, the operator will select now a shaft 21 having cutters 37 arranged to correspond to this second series of knobs. This is effected by releasing the locking pin 18 for the drum 6, Fig. 4, and then rotating said drum by means of the handles 36 until the selected second shaft 21 is in 95 operative relation to the body 8. The locking pin 18 is then restored to locking position, and after the slide clamp bearing 60 has been readjusted to fixedly hold the mandrel 50 at the reduced end, the operator again depresses the treadle arm 78 and then swings the lever 64 upward to bring 100 this second series of knobs into milling position.

In a similar way the operation may be 105 repeated with respect to a third series of knobs and the third assembly of bearing shafts and cutters. If then any one of the other series of knobs (six being illustrated in Fig. 8) should require a treatment by cutters which are spaced differently 110 from those at the present in the machine, or by cutters of different diameters (as for instance, in order to treat one or more knobs K' of the double valve system shown 115 in Fig. 14) the removal of the previously 120

125 130 135

used cutter shafts 20 may readily be effected by loosening the nuts 40 and withdrawing the respective cutter shafts 21 from the machine, replacing them by other shafts 5 which have cutters in proper arrangement and of proper diameter.

I claim:

1. In a machine of the character described, the combination of a support for 10 an instrument body, a plurality of tool shafts, a common support for said shafts at one end thereof, a second support for said shafts at the other end of the same, a central bar connecting both of said common supports, and means for selectively adjusting 15 one of said supports.

2. In a machine of the character described, the combination of a support for 20 an instrument body, a plurality of tool shafts, a common support for said tool shafts, shaft extensions mounted in said common support, and means for operatively and exchangeably connecting tool shafts with the shaft extensions of said common support. 25

3. In a machine of the character described, the combination of an instrument body, a plurality of tool shafts, a common support for said tool shafts, shaft extensions 30 rotatably mounted in said common support, and means for exchangeably maintaining the tool shafts in alinement with said shaft extensions.

4. In a machine of the character described, the combination of a support for 35 an instrument body, a plurality of tool shafts, a rotary drum, shaft extensions individually supported within said drum, said shaft extensions being provided with 40 ends projecting from the drum and means for detachably uniting the ends of said extensions with the ends of the tool shafts and for retaining the shafts in alinement with said extensions. 45

5. In a machine of the character described, the combination of a support for an instrument body, a plurality of tool shafts, a drum 50 rotatably mounted in the machine, a plurality of bearings circumferentially spaced in the interior of the drum, shaft extensions rotatably supported in said bearings and projecting from the drum, means for uniting the tool shafts with the projecting ends of the shaft extensions and in alinement thereto, a second common support for said tool shafts, a central bar extending through said drum and through said second support, and a cylindrical casing forming a bearing for 55 said drum. 60

6. In a machine of the character described, the combination of a support for an instrument body, a tool shaft, and means for adjusting the position of said support relatively to said tool shaft axially of said shaft 65 and in a horizontal and vertical plane. 70

7. In a machine of the character described, the combination of a support for a tapering instrument body having a plurality of parts in alinement within an axial plane of said body and distributed on the circumference 75 of the body, a tool shaft parallel to the axis of said body, and means for adjusting said support and body with respect to the tool shaft to bring the line on which said parts project from the body into parallelism with the axis of the tool shaft. 75

8. In a machine of the character described, the combination of a support for an instrument body, a tool shaft, a bearing for said support, means for locking said support within said bearing against circumferential displacement, and means for selectively adjusting said bearing in a horizontal plane and in a vertical plane with respect to said tool shaft. 80

9. In a machine of the character described, the combination of a support for an instrument body, a tool shaft, bearings at the two ends of the support, a common carrier for said bearings on which the bearings are axiallylly adjustable, said bearings being adjustable independently of each other on their carrier in a horizontal plane and being adjustable independently of each other in a vertical plane relatively to the shaft. 90

10. In a machine of the character described, the combination of a support for an instrument body, a tool shaft, a bearing for said support, means for locking the support against rotation within said bearing in selected predetermined position, a carrier for the bearing, and a bracket inserted between the carrier and the bearing, the bracket being longitudinally adjustable on the carrier and the bearing being rotatably adjustable 100 on the bracket relatively to the shaft. 105

11. In a machine of the character described, the combination of a suport for an instrument body, a bearing for said support, means for selectively locking said support within the bearing in a rotatable adjusting position, a carrier for the bearing, a bracket mounted on said carrier and supporting the bearing, said bearing being adjustable about an axis on said bracket, said bracket being 110 axially adjustable on the carrier and the carrier being tilttable about its own axis. 115

12. In a machine of the character described, the combination of a support for an instrument body, a rock shaft, clamps adjustably mounted on said rock shaft, bearings for the instrument body rotatably secured to said clamps, and means for imparting a rocking movement to said shaft. 120

13. In a machine of the character described, the combination of a support for an instrument body, a rock shaft, a bearing for said instrument body associated with the rock shaft, and means for preventing vertical displacement of said bearing relatively 125 130

to said rock shaft without preventing rotary adjustment of said bearing in a predetermined plane.

14. In a machine of the character described, the combination of a bearing for an instrument body, a rock shaft, a bracket axially adjustable on said rock shaft and having a cylindrical extension, said bearing having a cylindrical bore rotatably fitted to said extension, and means coacting with said bore and extension for preventing displacement of said bearing in direction to the axis of said extension, said bearing being rotatable on said extension.

15. In a machine of the character described, the combination of rotary tools, a support for an instrument body, a rock shaft, bearings for said support, brackets secured to said rock shaft and supporting said bearings, means for moving the rock shaft relative to the tools, and means for limiting the movement of said rock shaft in either direction.

16. In a machine for milling the knobs of a wind musical instrument, the combination of a tapered mandrel for the instrument body, said mandrel being movably supported in the machine, rotary tools in axial alignment with each other, means acting on said mandrel for bringing the instrument body into and out of operative relation with respect to said tools, and means for adjustably limiting the movement of said mandrel with respect to said tools.

17. In a machine for milling the knobs of a wind musical instrument, the combination of a tapered mandrel for the instrument body, said mandrel being movably supported in the machine, a plurality of tool shafts, a prime mover for the machine, means for selectively bringing any one of said tool shafts into operative relation with respect to said prime mover and said mandrel.

18. In a machine for milling the knobs of a wind musical instrument, the combination of a tapered mandrel, a hollow instrument body carried by the mandrel, a plurality of tool shafts, means for selectively moving any one of said shafts to operative relation with respect to the instrument body, a drive shaft, means for normally disconnecting said drive shaft from said tool shafts, and means for establishing a connection between said drive shaft and a selectively predetermined tool shaft.

19. In a machine for milling the knobs of a wind musical instrument, the combination of a tapered mandrel, a hollow instrument body mounted upon the mandrel, a plurality of tool shafts, means for moving any of said tool shafts into operative relation with respect to the instrument body, a prime mover, a drive shaft, a transmission between said prime mover and drive shaft, said transmission being normally inoperative, and means

for simultaneously rendering said transmission operative and for establishing a connection between the drive shaft and the tool shaft placed into operative relation.

20. In a machine for milling the knobs of a wind musical instrument, the combination of a tapered mandrel to support the instrument body, a plurality of tool shafts arranged in a circular series about a common axis, means for selectively bringing any of said shafts into operative relation with respect to said body, a prime mover, a drive shaft, coupling members on said tool shafts, means for normally maintaining said coupling members out of operative relation, and means for simultaneously effecting actuation of said drive shafts from the prime mover and for bringing predetermined coupling members into operative relation.

21. In a machine for milling the knobs of a wind musical instrument, the combination of a tapered mandrel to support the instrument body, a plurality of tool shafts each terminating in a coupling member, a drive shaft having a coupling member, means for selectively moving any of said tool shafts to operative relation with respect to the instrument body, driving means for the drive shaft normally inoperative, and means for rendering said last named means operative and for establishing connection between the coupling member of the drive shaft and the coupling member of a selectively predetermined tool shaft.

22. In a machine of the character described, the combination of a mandrel for an instrument body, said mandrel being movably supported in the machine, a plurality of tool shafts, means for selectively moving any one of said tool shafts to operative position, a drive shaft, a pulley driven thereby, a prime mover, a belt transmission normally inoperative between said pulley and prime mover, and means for simultaneously rendering said belt transmission operative and moving said drive shaft into operative relation with a selectively predetermined tool shaft.

23. In a machine of the character described, the combination of a plurality of tool shafts, means for selectively placing any one of said tool shafts in operative connection with respect to an instrument body, a drive shaft, a motor, a belt transmission extending from said motor to said drive shaft and normally slack to prevent transmission of power, and means for simultaneously tensioning the belt and axially displacing the drive shaft in operative relation with respect to a selectively predetermined tool shaft.

24. In a machine of the character described, the combination of a support for an instrument body, a plurality of tool shafts adapted to be brought into operative relation thereto selectively, a drive shaft, a pulley

fixedly connected with said drive shaft, a motor, a transmission belt between said pulley and motor, a tensioning device for the belt, a treadle shaft, connecting elements extending from said treadle shaft to said drive shaft, connecting elements between said treadle shaft and the tensioning device, and

means for simultaneously operating the two sets of connections to force the drive shaft into operative relation and to tension the belt.

In witness whereof I have hereunto affixed my signature 27th day of October, 1922.

EDWARD J. GULICK.
